UNITED STATES PATENT OFFICE.

WINFIELD A. ATWOOD, OF SCHENECTADY, NEW YORK, ASSIGNOR TO GENERAL ELECTRIC COMPANY, A CORPORATION OF NEW YORK.

ELECTRIC SWITCH.

Application filed April 21, 1924. Serial No. 707,832.

My invention relates to improvements in electric switches and more particularly to improvements in electric switches adapted to be used as auxiliaries in the control of circuit breakers and the like.

When automatic circuit breakers of the latched-in type are arranged to be closed by solenoids, motor mechanisms and the like, it is desirable that the closing means remain energized until the circuit breaker is positively latched. Then the closing means should be deenergized quickly in order to prevent waste of power and any tendency to overheat the energizing windings and, what is more important, to give the fault responsive means full control of the circuit breaker in case it has been closed on a faulty circuit. In order to insure the desired operation, auxiliary devices operative with a time lag are employed. These devices may be actuated electrically as in the case of control relays or mechanically as in the case of auxiliary switches associated with the circuit breaker closing mechanism. In either case, it is necessary especially when large circuit breakers are to be operated, and particularly solenoid operated, to provide a relatively high current interrupting capacity.

An object of my invention is, therefore, to provide an improved electric switch which has a mechanically delayed action, especially in opening, and which is particularly adapted for direct mechanical connection to the closing mechanism of a circuit breaker so as to control the energizing of the closing mechanism, particularly with reference to a predetermined position of the circuit breaker mechanism. Another object of my invention is to provide a comparatively simple form of switch which is conveniently adjustable so as always to ensure positive operation at the desired instant and which has the requisite current interrupting capacity.

My invention will be better understood from the following description taken in connection with the accompanying drawings and its scope will be pointed out in the appended claims.

Figs. 1 and 2 show in elevation an embodiment of my invention in circuit closed and open positions respectively, Fig. 3 shows in elevation a modification of my invention in circuit closed position, and Fig. 4

shows partly in elevation and partly in diagram the embodiment of my invention shown in Figs. 1 and 2 as applied to a solenoid operated circuit breaker.

The embodiment of my invention illustrated in Figs. 1, 2 and 4 comprises relatively movable cooperating contacts 1 and 2 which are mounted on a frame or body 3 adapted for mounting on a switchboard 4 or the like. The fixed contact 1 is suitably insulated from the frame 3 and the movable contact 2 is mounted on an arm 5 carried on a pivot 6 in the frame 3. The movable contact 2 may be provided with a secondary or carbon contact 7, especially when relatively large currents have to be interrupted as is often the case with solenoid-operated high capacity circuit breakers.

For moving the contact 2 to and from circuit closing position, I provide an actuating member such as a crank 8 which is carried on a pivot 9 in the frame 3 and which is connected to the arm 5 by a pivot 10. The crank 8 is arranged so that upon movement in one direction, clockwise with reference to Figs. 1, 2 and 4, the contact 2 is moved to circuit closing position and upon movement in the opposite direction, counter clockwise with reference to Figs. 1, 2 and 4, the contact 2 is moved to circuit opening position. Since the arm 5 and crank 8 are arranged for movement on pivots 6 and 9 respectively and these pivots are fixed relatively to the pivot 10, the hole 10' in the crank 8 through which the pivot 10 passes is made larger than the diameter of the pivot 10 in order to permit movement of the pivot 10 in a path across the line through pivots 6 and 9. The circuit opening movement is preferably very quick, especially at the beginning, so as to provide snap action at the contacts. This movement is obtained by a biasing spring 11 connected between the pivot 6 and a pin 12 near the end of one arm of the crank 8 so as to have energy stored in it during the contact closing motion of the crank 8 and to tend to turn the crank in the contact opening direction.

For actuating the crank 8 in contact closing direction, I provide suitable means such as an operating member 13 carried on a pivot 14 in the frame 3. A roller 15 mounted on the operating member 13 is arranged to engage a curved portion 16 on the crank 8 upon movement of the operating member

13 in one direction, counter-clockwise with reference to Figs. 1 and 2. In order to restrain the crank 8 from movement to contact opening position under the bias of spring 11 until a predetermined movement of the operating member 13, I provide a restraining member 17 carried on the pivot 14 and arranged to slide over a curved or arcuate portion 18 of the crank 8, the center of curvature of which is, in the contact closing position of the crank, in the axis of the pivot 14. For moving the restraining member 17 from restraining position, it is arranged to abut the operating member 13 so that upon a predetermined clockwise movement of the operating member, the restraining member 17 is moved clear of the arcuate portion 18 of the crank 8 as shown in Fig. 2. When the restraining member 17 is thus moved from restraining position, the crank 8 is free to move to contact opening position under the bias of the spring 11, and the parts are positioned substantially as shown in Fig. 2. The contact opening movement of the crank 8 may be limited in any suitable manner such as having the pivot 10 abut extensions on the side portions of the frame 3.

In order to return the restraining member 17 to restraining position when the switch is closed, I provide suitable biasing means such as a spring 19 arranged to have energy stored therein upon counter-clockwise movement of the operating member 13. This spring may be of the torsion type having its ends secured to the restraining and operating members respectively. The operating member 13 is thus arranged to effect movement of the restraining member 17 to restraining position.

In Fig. 4, I have illustrated my invention as applied to the control circuit of a solenoid 20 arranged when energized to close a circuit breaker 21. The control circuit of the solenoid 20 is connected across a supply bus 22 and includes in series with the solenoid coil, a normally open control switch 23 and the contacts 1 and 2 of an auxiliary switch such as shown in Figs. 1 and 2. The operating member 13 of the auxiliary switch is connected directly to the rock shaft 24 of the circuit breaker closing mechanism 24 by a link 25 and a crank 26 so that the contacts 1 and 2 are closed when the circuit breaker 21 is open, and are opened when the circuit breaker is closed sufficiently to be latched positively. In this way, it is impossible for an operator to hold the circuit breaker 21 closed on a faulty line by keeping the switch 23 closed.

The link 25 is shown more in detail in Figs. 1 and 2 and may comprise two threaded portions 27 and 28 of different pitch so as to provide a micrometer adjustment for the position of the operating member 13

with respect to the latched-in position of the circuit breaker 21 in order to insure that the restraining member 17 will be moved clear of the crank 8 at the right instant.

In the embodiment of my invention shown in Fig. 3, the fixed and movable contacts 1 and 2 are supported by a frame 3, the movable contact being mounted on an arm 29 carried on a pivot 30. The restraining member 17' and the operating member 13' are carried by a pivot 31 in the frame 3 and the restraining member is provided with an arcuate or curved flange 32 against which a projecting portion 33 of the arm 29 is arranged to abut so as to restrain the movable contact 2 from moving to circuit opening position until a predetermined movement of the operating member 13'.

In order to close the switch, the arm 29 is provided with a projection such as a pin 34 arranged to abut and slide on a portion 35 of the operating member 13'. Similarly, in order to move the restraining member 17' from restraining position, it is provided with a projection such as a pin 36 arranged to abut the edge 37 of the operating member 13'. For moving the restraining member 17' to restraining position and the contact 2 to circuit opening position, a biasing spring 38 connected between the pins 34 and 36, is provided.

Assuming the parts positioned as shown in Fig. 3, it will be clear that, when the operating member 13' is moved clockwise, it will bear against the pin 36 and thereby move the restraining member clockwise. But, as the portion 33 of the arm 29 abuts the flange 32 of the restraining member 17', the arm 29 cannot move until the flange 32 has been moved clear of the projecting portion 33. Consequently, energy is stored in the spring 38 so that upon a predetermined clockwise movement of the operating member 13', the restraining member is moved sufficiently for the flange 32 to release the arm 29 which is then quickly snapped to the circuit opening position. The circuit opening position of the arm 29 is limited by the pin 34 coming to rest against the portion 35 of the operating member 13'. When the operating member 13' is moved counter-clockwise, the pin 34 abuts the portion 35 of the operating member and moves the arm 29 to contact closing position. During this circuit closing movement, however, the projecting portion 33 of the arm 29 is not high enough to slide over the flange 32 of the restraining member 17' so that the spring 38, because of the relative movement of the restraining member 17' and the arm 29, again has energy stored in it. This energy is available to move the restraining member to restraining position when the arm 29 has been turned sufficiently to raise its projecting portion 33 high enough to allow movement of the flange 32 thereunder.

It will be obvious that in this modification the construction is simpler and the number of parts less than in the switch shown in Figs. 1 and 2, but in principle the operation is substantially the same and in each modification the construction is such that a predetermined movement of an operating member, which may be actuated in any suitable manner, is necessary to effect the opening of the switch so that the opening may be made synchronous with any predetermined operation or position of a device with which the operating member is associated.

While I have shown and described in detail several embodiments of my invention and described its application particularly to circuit breakers, it is obvious that it is not limited to the particular arrangements or application described and I therefore aim in the appended claims to cover all such variations and modifications as fall within the spirit of my invention.

What I claim as new and desire to secure by Letters Patent of the United States, is:

1. In an electric switch of the class described, relatively movable cooperating contacts, restraining means for holding said contacts in circuit closing position arranged to be held from restraining position while the contacts are in the circuit open position, and an operating member for actuating one of said contacts arranged upon movement in one direction to move said contacts to circuit closing position and upon a predetermined movement in the opposite direction to move said restraining means from restraining position whereby to permit movement of said contact from circuit closing position, and means for effecting the movement of the restraining means to restraining position after said contact is in circuit closing position arranged to have energy stored therein by the movement of the operating member in the circuit closing direction.

2. In an electric switch of the class described, relatively movable cooperating contacts, an operating member movable in one direction to close said contacts, a restraining member for preventing movement of said contacts to circuit opening position movable to restraining position only when said contacts are in circuit closing position and arranged to be moved from restraining position by said operating member upon a predetermined movement thereof in the opposite direction, and a spring arranged to have energy stored therein by said operating member upon movement thereof in a direction to close said contacts whereby to bias said restraining member to restraining position.

3. In an electric switch of the class described, relatively movable cooperating contacts, an actuating member movable in one direction to close said contacts and comprising

an arcuate portion, resilient means arranged to have energy stored therein upon movement of said actuating member in the direction to close said contacts whereby to bias said actuating member for movement in the opposite direction to open said contacts, a restraining member pivoted for movement on an axis through the center of curvature of the arcuate portion of said actuating member when the actuating member is in the contact closing position, and an operating member arranged upon movement in one direction to move said actuating member to contact closing position and to effect movement of said restraining member over the arcuate portion of said actuating member whereby to prevent movement of said actuating member from contact closing position and upon a predetermined movement in the opposite direction to move said restraining member clear of the arcuate portion of said actuating member whereby the actuating member is free to move from contact closing position.

4. In an electric switch of the class described, relatively movable cooperating contacts, an actuating member adapted to be operated to move one of said contacts to and from circuit closing position and comprising a plurality of curved portions, a restraining member for holding said actuating member in the contact closing position movable in a path having substantially the same curvature as and concentric with one of the curved portions of said actuating member when the actuating member has been moved to the contact closing position, and an operating member arranged upon movement in one direction to engage another curved portion of said actuating member whereby to move the actuating member to the contact closing position, and to effect movement of said restraining member in a direction to engage and hold said actuating member in the contact closing position and upon a predetermined movement in the opposite direction to move said restraining member clear of said actuating member whereby the actuating member is free to move from the contact closing position.

5. In an electric switch of the class described, relatively movable cooperating contacts, an actuating member movable in one direction to close said contacts, a spring arranged to have energy stored therein upon movement of said actuating member in contact closing direction whereby to bias said actuating member for movement in the opposite direction to open said contacts, a restraining member arranged to slide over a portion of said actuating member when the actuating member has been moved to contact closing position whereby to prevent movement of said actuating member in said opposite direction, an operating member ar-

1
ranged upon movement in one direction to engage and move said actuating member in a direction to close said contacts and upon a predetermined movement in the opposite direction to move said restraining member clear of said portion of the actuating member, and a spring arranged to have energy stored therein upon movement of said operating member in a direction to move said

actuating member to contact closing position 10 whereby said restraining member is biased for movement in a direction to slide over said portion of the actuating member when the actuating member has been moved to contact closing position. 15

In witness whereof, I have hereunto set my hand this 19th day of April, 1924.

WINFIELD A. ATWOOD.
